UNITED STATES PATENT OFFICE.

HENRY C. WILDER, OF ASHBY, MASSACHUSETTS, ASSIGNOR OF ONE-HALF
TO JOEL G. WILLARD, OF NEW YORK, N. Y.

SAFETY-VALVE.

SPECIFICATION forming part of Letters Patent No. 322,084, dated July 14, 1884.

Application filed December 10, 1884. (No model.)

To all whom it may concern:

Be it known that I, HENRY C. WILDER, of 5
Ashby, in the county of Middlesex and State
of Massachusetts, have invented a certain new
and useful Improvement in Safety-Valves, of
which the following is a specification.

This improvement relates to safety-valves
in which springs are employed to resist the
force tending to move the valve away from its
seat.

I will describe a safety-valve embodying my
improvement, and then point out the improve-
ment in claims.

In the accompanying drawings, Figure 1 is
15 longitudinal section of a safety-valve embody-
ing my improvement. Fig. 2 is a longitudi-
nal section taken in a plane at right angles to
that of Fig. 1. Fig. 3 is a transverse section
thereof taken on the lines *x x*, Fig. 1. Fig. 4
20 is a detail view thereof. Fig. 5 is a longitudi-
nal section of a valve, showing a modification
thereof. Fig. 6 is a sectional detail view of
the same, and Fig. 7 is another sectional de-
tail view of the same.

25 Similar letters of reference designate corre-
sponding parts in all the figures.

A designates the frame of the valve by which
the various parts are supported. As shown,
it consists of two arm-like portions, *a a'*, fast-
30 upon a base-piece, B, and bearing at their
ends a cylindrical rim-like portion, C. The
said arm-like portions, the base-piece, and
the ring-like portion are preferably made in-
tegral.

35 The base-piece B is of circular form and
hollow. It extends for a considerable dis-
tance laterally beyond the arm-like portions
a a'. This is to afford provision for the
escape of steam through apertures *b* in the up-
per portion of the base-piece B.

A coupling-piece, D, is adapted to be screwed
into the lower portion of the base-piece B.
Said coupling-piece is adapted to be secured
in any suitable manner to a steam-boiler. Near
45 its upper end the coupling-piece constitutes a
valve-seat for a valve, E. Guides *c* on the
valve E guide the valve in its movements. A
recess in a projection, *c'*, in the upper portion
of the valve is adapted to receive one end of
50 a pin, F. The valve is further guided in its

movements by the projection *c'*, which is adapt-
ed to move through an aperture in the upper
portion of the base-piece B. As shown, the
outwardly-extending end of the pin F is bi-
furcated.

55 G is a lever fulcrumed near one end upon a
fulcrum-piece, *d*, forming part of the frame
A. About midway of its length the lever G
is recessed upon its under side to receive the
bifurcated end of the pin F. It will be seen 60
that when the valve E is raised from its seat
it operates to move the lever G, through the
medium of the pin F.

H is an adjustable section of the lever G.
It is adapted to be moved backward and for-
ward upon the upper surface of the lever G. 65
Owing to the contour of the upper surface of
the lever G the adjustable section H may be
moved thereon in a direction obliquely to the
direction of the movement of the valve.

A set-screw, I, engaging with one end of
the adjustable section H, and bearing at its
free end upon the main section of the lever G,
may be adjusted to vary the position of the
adjustable section H upon the main section of 75
the lever G. Guides *e e'* on the main section
of the lever G guide the adjustable section H
in its movements.

J is a spring, shown as helical, arranged
between the arm-like portions *a a'* of the frame 80
A. Bearing-pieces K K' are arranged one
upon each end of the spring J. The bearing-
piece K is provided with a projection, *f*, upon
its lower side. Such projection is preferably
knife-edged at its lower extremity, and is 85
adapted to bear upon the upper surface of the
adjustable section H of the lever G. The
bearing-piece K' is provided upon its upper
surface with a projection, *g*, adapted to receive
a knife-edged projection, *h*, upon the inner end 90
of a cylindrical plug, L, fitting within the rim-
like portion C of the frame A, and secured
therein by screws or otherwise. The plug L
may be adjusted inwardly and outwardly to
vary the resistance of the spring J. Obvi- 95
ously the knife-edge may be arranged upon
the bearing-piece and the projection which re-
ceives it upon the plug, if desirable.

I preferably combine with the lever G a de-
vice whereby the valve may be opened at 100

pleasure. A convenient form of device for this purpose is shown in the drawings. It consists of a lever, M, having a bifurcated end extending between the arm-like portions *a a'* 5 of the frame A. The bifurcate arms of the lever pass one upon each side of the pin F, and so as not to interfere with the rising of the valve. A projection or rib, *i*, upon the upper surface of the lever M, is shown for 10 acting against the lever G. By manipulating the lever M the valve E may be raised from its seat.

N is a cylindrical case or shell adapted to inclose the parts. It may be moved on and off 15 longitudinally at pleasure.

Steam entering the coupling-piece D operates to raise the valve E from its seat. Force is thereupon exerted upon the lever G by means of the pin F, which force the spring J 20 has a tendency to counteract. As the lever G is raised, however, it operates to oscillate the spring J in one direction, thus shifting the point upon the lever where the resistance of the spring is exerted, and moving such point 25 of resistance more and more out of the line of application of force exerted by the escaping steam. By this arrangement the tendency of the resistance of a spring to increase when arranged to receive the application of a force 30 exerted to overcome such resistance in a direct line is overcome, and the danger arising from sudden and undue increase of boiler-pressure is averted.

By varying the position of the adjustable section H of the lever G, the valve may be set 35 to operate at any desired steam-pressure, as by such variation the resistance of the spring may be increased or decreased.

In the example of my improvement shown 40 in Figs. 5, 6, and 7 the frame A, as shown in Figs. 1, 2, and 3, is not needed, and for this reason the shell N and the base-piece B are preferably made integral.

O designates a frame having a circular base 45 portion, *o*, and arm-like portions *o'*. A semi-circular connecting-piece, *o*², extends between the arm-like portions *o'*, but the same may be omitted. In this example of my improvement the pin F is preferably made integral with 50 the frame O. A projection, *o*³, upon the under side of the circular base portion *o* of the frame serves to raise said base portion somewhat above the bottom of case or shell N.

The spring J is arranged within the frame 55 O. The lower end of the spring rests upon a bearing-piece, K. A screw, *p*, passing through a screw-threaded aperture in the projection *o*³ on the base portion *o*, is affixed to the bearing-piece K. A bearing-piece, K', is arranged upon the opposite end of the spring 60 J. Said bearing-piece has a knife-edged projection upon its upper surface adapted to bear upon the adjustable section H, arranged beneath and adapted to be moved backward and forward within guides upon the lever G. 65 The lever G is fulcrumed at *r* upon downwardly-extending parts of the arm-like por-

tions *o'* of the frame O. Pins or projections *s* on the lever G are adapted to abut against projections *s'* near the upper end of the arm-like portions *o'*, and prevent the lever G from moving so far in one direction as it would otherwise do.

The set-screw I has upon it a circumferential rim adapted to engage with a slot in the 75 adjustable section H of the lever G, whereby, when the screw is turned, it will carry with it in its forward and backward movement the said adjustable section. A stop, *t*, on the adjustable section H prevents a too-extended 80 movement in one direction.

The knife-edged projection upon the cylindrical plug L bears upon the upper surface of the lever G.

By adjusting the screw *p* inwardly or outwardly the resistance of the spring J may be varied.

The operation of this example of my improvement is that of toggle-levers, of which the frame O constitutes one lever, and the 90 lever G the other. When pressure is exerted upon the valve, it operates to raise the frame or lever O. The lever G is then caused to be moved against the resistance of the spring J, the result being that the levers are oscillated. 95

What I claim as my invention, and desire to secure by Letters Patent, is—

1. In a safety-valve, the combination of a valve, a lever having an adjustable section, a connection between the valve and the lever, 100 and a spring exerting force at one end against the adjustable section of the lever for operating the lever in one direction, substantially as specified.

2. In a safety-valve, the combination of a 105 valve, a lever having an adjustable section, a connection between the lever and the valve, a spring exerting force at one end upon the adjustable section of the lever, and at the other end upon an adjustable bearing-point, substantially as specified.

3. In a safety-valve, the combination of a valve, E, a pin, F, a lever, G, fulcrumed upon a fixed portion of the frame of the valve, and having an obliquely-adjustable section, H, the 115 spring J, and the plug L, substantially as specified.

4. In a safety-valve, the combination of a valve, E, a pin, F, a lever, G, fulcrumed upon a fixed portion of the frame of the valve, and 120 having an obliquely-adjustable section, H, the spring J, and the trip M, substantially as specified.

5. In a safety-valve, the combination of a frame, A, having the base-piece B, extending 125 beyond the main or upper portion of the case or shell, apertures *b* in the base-piece B, the valve E, the pin F, the lever G, and the spring J, substantially as specified.

HENRY C. WILDER.
